UNITED STATES PATENT OFFICE

2,119,780

AGGREGATE HANDLING APPARATUS

Henry O. Curtis, Des Moines, Iowa

Application April 17, 1937, Serial No. 137,480

6 Claims. (Cl. 214—110)

One object of my invention is to provide apparatus for handling aggregate such as sand, gravel and the like for conveying such aggregate to an aggregate mixer, such as a concrete mixer, the apparatus being comparatively simple and durable as well as inexpensive from a manufacturing standpoint.

A further object is to provide an aggregate handling apparatus including a wheeled container and doors pivoted to the open ends thereof, which are so movable through the aggregate as to facilitate their closure after the aggregate container has been filled.

Still a further object is to provide a wheeled aggregate carrier having a reversible bail pivoted thereto for propelling it by means of winch and cable mechanism.

Another object is to provide doors for the aggregate carrier which are opened and closed by the reversible bail during its operation.

Still another object is to provide an inclined track for the aggregate carrier so associated with a concrete mixer that the carrier can be propelled up the track and to a position for discharging its contents into the concrete mixer.

With these and other objects in view, my invention consists in the construction, arrangement and combination of the various parts of my aggregate handling apparatus, whereby the objects contemplated are attained, as hereinafter more fully set forth, pointed out in my claims, and illustrated in the accompanying drawing, in which:

Figure 1 is a side elevation partly in section showing an aggregate carrier forming a part of my aggregate handling apparatus.

Figure 2 is a plan view of the carrier.

Figure 3 is a diagrammatical side elevation of the carrier and the remaining part of the apparatus for conveying aggregate to a concrete mixer; and

Figure 4 is a side elevation of a modified form of carrier.

On the accompanying drawing I have used the reference character C to indicate a container for aggregate. The container C has a pair of side walls 10 and a bottom 11, the ends of the container being open. Wheels 12 are provided for supporting the container C so that it can be readily propelled from one position to another.

The open ends of the carrier C are closed by doors D and D' pivoted to the upper corners of the carrier as at 13. Each of the doors D and D' comprises an arcuate end member 14 curved on a radius from the pivotal axis 13, and a pair of

side members 15. The specified curvature of each end member 14 enables closure of these doors through the aggregate after the container C is propelled into the pile of aggregate with the door open.

For propelling the aggregate container or carrier C I provide a bail 16, a winch 17 (see Figure 3) and cables 18. The bail 16 is pivoted to the carrier C as at 19 so it can be reversed as illustrated by solid and dotted lines in Figure 1.

When the bail 16 is in the solid line position, the aggregate carrier is propelled in a left hand direction into the pile of aggregate. It will be noted that the door D is opened, such opening being automatically effected by a jackknife toggle arrangement including a pivoted lever 20, a door lever 22 and link connections 23 and 24. The link connection 23 extends from the bail 16 to the lever 20, while the link connection 24 extends from the lever 20 to the lever 22.

When the bail 16 is reversed, the jackknife toggle arrangement will straighten out to the dotted position for closing the door 14 and thereby retaining the aggregate in the container C when the container is propelled in a right hand direction.

A flexible connection 25 is provided between the lever 16 and the door D' for closing this door whenever the carrier is propelled in a left hand direction and for permitting it to open when it is propelled in a right hand direction.

The door D' is normally retained closed by a latch 26 engaging a cross rod 27 on the door. A leaf spring 28 serves to normally retain the latch in the latching position. The latch is provided with an extension 29 adapted, as will hereinafter appear, to be engaged during the operation of the aggregate carrier for unlatching the door automatically.

In Figure 3 further elements of the apparatus are illustrated. An inclined track 30 is provided which may be mounted on a truck T. The track 30 is made of a pair of channel irons spaced laterally and adaptable for receiving the wheels 12, and thereby guiding the carrier to a position where it can discharge into the chute 31 of a concrete mixer 32.

The latch extension 29 is adapted to engage a stationary projection 33 for thus releasing the door D' after which a stationary extension 34 engages a lever 35 of the door D' for opening the door so the contents of the container C may be discharged into the concrete mixer 32.

The winch and cable mechanism includes idler pulleys 36, a dead man pulley 36' and a boom 37.

carrying an idler pulley 38. The boom 37 is pivoted to the truck T and may move between stops 39 during operation.

In Figure 4 I illustrate a modified form of construction in which a carrier C' is provided with an open end 40 which is constricted by inclining the forward ends of the sides of the carrier toward each other. In this way the discharge end of the carrier C' may enter the intake opening 41 of a concrete mixer 32' for discharging the contents thereto without spilling them. This carrier is illustrated as having a manually operable door D" provided with a handle lever 35' and a latch 42 is illustrated for latching the door D" in closed position.

Aside from these features, the carrier C' is similar in construction to the carrier C, but does not have all of its automatic advantages.

Practical operation

In the operation of my device, referring to Figure 3, the carrier C is being moved in a left-hand direction and pulled into a pile of aggregate 43. The door D is open, as shown by solid lines in Figure 1, so the aggregate can enter the carrier C, but will be retained against falling out of the forward end thereof by the door D' latched in closed position by the latch 26.

When the carrier has been filled, the winch 17 is reversed for swinging the bail 16 of the carrier from the full line position to the dotted position, which first closes the door D and then propels the carrier up the inclined track 30, as shown by dotted lines. Finally as shown by dash lines, the carrier travels down the inclined portion 30' of the track 30, the latch 26 being unlatched adjacent the end of its downward travel and thereafter the extension 34 engaging the handle lever 35 and thereby opening the door D'. This permits the contents of the aggregate carrier to be discharged into the chute 31 from which the aggregate slides into the mixer 32.

Just before reaching the height of its travel on the inclined track 30, the bail 16 will engage the pulley 38 of the boom 37 and swing the boom forwardly to the dash line position, thereby raising the forward end of the bail to an out-of-the-way position where it does not interfere with the concrete mixer 32. This position is illustrated in Figure 4.

After the contents of the carrier have been discharged, the winch 17 is again reversed for reversing the bail 16 and propelling the aggregate carrier C back for another load of aggregate.

With the construction shown in Figure 4, it is not necessary to release and open a door at the right hand end of the carrier.

A modification of the character shown in Figure 4, when compared with the construction shown in Figure 1, and many others may be made without departing from the real spirit and purpose of my invention, and it is my intention to cover by my claims any modified forms of structure or use of mechanical equivalents which may be reasonably included within their scope.

I claim as my invention:

1. In an aggregate handling apparatus, a wheeled container having open ends, doors for said ends, a bail pivotally connected to said con-

tainer for reversal relative thereto for pulling said container in either direction, and an operative connection between said bail and said doors to close one door when the bail extends in one direction and to close the other door when the bail extends in the other direction. 5

2. In an aggregate handling apparatus, a wheeled container having open ends, doors for said ends, said doors being pivoted to said container and being formed on radii from the pivot 10 axes, a bail pivotally connected to said container for reversal relative thereto for pulling said container in either direction, and an operative connection between said bail and said doors to close one door when the bail extends in one direction 15 and to close the other door when the bail extends in the other direction.

3. In an aggregate handling apparatus, a wheeled container having open ends, a door for one of said ends, a bail pivotally connected to the 20 lower part of said container adjacent the center thereof and reversible by swinging fore and aft across the top thereof for pulling said container in either direction, and an operative connection between said bail and said door to close 25 the door when the bail extends in one direction from its pivotal connection.

4. In an aggregate handling apparatus, a wheeled container having open ends, a door for one of said ends, a bail pivotally connected to said 30 container and reversible by swinging fore and aft across the top thereto for pulling said container in either direction, and a toggle lever connection 35 between said bail and said door to close the door when the bail extends in one direction from its pivotal connection and to open the door when the bail extends in the other direction therefrom.

5. In an aggregate handling apparatus, a wheeled container having open ends, a door for one of said ends, a track for said container terminating adjacent the intake of an aggregate 40 mixer and winch and cable mechanism for alternately propelling said container into a pile of aggregate and along said track to discharge its contents into said mixer, said container having a bail connected to the lower center portion thereof with its outer end connected with said winch and cable mechanism, such bail connection being swingable across the top of said container and thereby reversible for pulling the container in either direction. 45

6. In an aggregate handling apparatus, a wheeled container having open ends, a door for one of said ends, a track for said container terminating adjacent the intake of an aggregate 55 mixer and winch and cable mechanism for alternately propelling said container into a pile of aggregate and along said track to discharge its contents into said mixer, said container having a bail connected with said winch and cable mechanism, such bail connection being reversible for pulling the container in either direction, and a boom pivoted adjacent said aggregate mixer and adapted to be engaged by said bail and raise it to a position where it does not interfere with the mixer as the container assumes a position there- 60 adjacent for discharging its contents. 65
